US00D623411S

(12) **United States Design Patent**
Cobabe et al.

(10) **Patent No.:** **US D623,411 S**
(b5) **Date of Patent:** **** Sep. 14, 2010**

(54) **BRUSH HEAD FOR CLEANING APPARATUS**(75) Inventors: **Aaron D. Cobabe**, Syracuse, UT (US);
David O. Meyers, Kaysville, UT (US);
Darrell E. Goff, Highland, UT (US); **W. Kenneth Thiess**, Parker, CO (US)
